SHADOWPROOF DRESS

Harriet G. Lewis, Brooklyn, N. Y.

Application August 14, 1950, Serial No. 179,180

2 Claims. (Cl. 2—75)

1

This invention relates to new and useful improvements in dresses for children.

One object of the invention is the provision of a child's dress having a petticoat fixed therein so that the dress may be made of light, almost transparent, material and yet will provide adequate coverage.

Another object of the invention of a child's dress openable from top to bottom at the rear and having a petticoat fixed therein and openable also.

Still another object is to construct and arrange the dress and the petticoat therein so that each is openable independently of the other.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front view of a dress embodying the invention with the sashes open and depended along the sides.

Fig. 2 is a rear view of the dress but with the sashes tied into a bow.

Fig. 3 is a fragmentary rear view illustrating the dress and the petticoat in open condition.

Fig. 4 is a fragmentary rear view illustrating the dress in open condition and the petticoat in closed condition.

Fig. 5 is an enlarged fragmentary sectional view on line 5—5 on Fig. 2.

Referring to Figs. 1 and 2, the invention is shown applied to a child's dress having a bodice portion 10 and a skirt 11, and shoulder straps or suspenders 12 to support the same on a child. It will be understood, however, that the dress may also include shoulder and sleeve portions if such are desired.

Preferably the shoulder straps 12 are secured to the front of the bodice portion 10 and are connectable with the rear portion of the bodice by means of buttons 13; and the skirt 11 has secured to the lower portion thereof a strip 14 of suitable decorative material.

The dress preferably at its rear is slit vertically from the upper to the lower edge thereof, the edges of said slit being folded back and secured by stitching to form hems 15, as best shown in Fig. 3. The two hemmed edges of the dress are connectable together by means of buttons 16 secured to one hem 15 and engaging buttonholes 17 formed in the other hem. The buttons 16

16 and the buttonholes 17 are, of course, spaced a suitable distance apart vertically.

Referring particularly to Figs. 3 and 4, a petticoat 18 is secured within skirt 11 in a manner to be described hereinafter and is slit vertically coincidently with the slit in the skirt. The edges of the slit in the petticoat are folded over and secured in place to form hems 20. Vertically spaced buttons 21 are secured to one hem 20 for engagement with buttonholes 22 to connect together the two halves of the petticoat. Preferably the buttons 21 are located on the same side of the slit in the petticoat as are the buttons 16 secured to the skirt. For beauty, the lower edge

15 of the petticoat is trimmed with lace 23.

The manner in which the bodice 10, the skirt 11 and the petticoat 18 are secured together is best illustrated in Fig. 5. The material of the bodice is of double thickness and its lower edge is bound by a tape 24. The upper edge of the skirt 11 is folded over the upper edge of petticoat 18 as shown at 25, and stitches 26 secure said fold-over against the inner face of the tape 24. Thus, the bodice, the skirt and the petticoat are secured together by the stitching 26.

In order that the edges of the skirt can be folded back to facilitate manipulation of the buttons 21 of the petticoat, the connection between the upper edges of the petticoat and the skirt is discontinued at the far edges of the hems 15 and 20, as shown in Figs. 3 and 4. That is to say, the hems 15 are not secured to the upper ends of the hems 20.

As shown in Figs. 1 and 2, sashes 30 have their ends secured to the juncture of the bodice 10 and the skirt 11 at the sides of the garment. The free ends of the sashes 30 are to be extended to the rear of the garment over the tape 24, see Fig. 5, to be tied together into a bow 31, as shown in Fig. 2.

Preferably the material of the skirt 11 and the bodice 10 is extremely thin and almost transparent for coolness in warm weather; thus, the petticoat 18, even though of light material itself, is needed to provide the necessary opaqueness.

It is to be mentioned that supporting the petticoat in the skirt, as taught by the invention, is extremely advantageous as it eliminates the need for an uncomfortable waist-constricting elastic band to support the petticoat as was the case heretofore.

It is to be understood that if desired, the petticoat 18 may be made detachable from the skirt as

by a zipper or the like and that the garment may also be completely or partly closed.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A child's dress of thin almost transparent material comprising a two-ply bodice portion slit vertically at the rear thereof, a skirt slit vertically the length thereof at the rear in vertical alignment with the slit of said bodice portion, a petticoat slit vertically the length thereof at the rear in alignment with the slit of said skirt, a hem on each side of the slits in the skirt and bodice, a hem on each side of the slit in the petticoat, taping binding the lower edges of the bodice, stitching securing the upper edges of the skirt and the petticoat to said taping, the skirt throughout its entire length but the petticoat only from one said hem to the other, the said hems being free, a plurality of vertically spaced buttons and buttonholes for securing together the hemmed edges of the skirt and the bodice, and a plurality of vertically spaced buttons and

5

buttonholes for independently securing together the hemmed edges of the petticoat.

2. A child's dress of thin almost transparent material comprising a two-ply bodice portion slit vertically at the rear thereof, a skirt fully slit vertically the length thereof at the rear in vertical alignment with the slit of said bodice portion, a petticoat fully slit, vertically the length thereof at the rear in alignment with the slit of said skirt, a hem on each side of the slits in the skirt and bodice, a hem on each side of the slit in the petticoat, taping binding the lower edges of the bodice, stitching securing the upper edges of the skirt and the petticoat to said taping, the skirt throughout its entire length but the petticoat only from the one said hem to the other, means to secure the hemmed edges of the skirt and bodice, and means to independently secure together the hemmed edges of the petticoat.

HARRIET G. LEWIS.
